UNITED STATES PATENT OFFICE.

ANDREW HYDE, OF HATFIELD, MASSACHUSETTS.

HEAD OF STRINGED MUSICAL INSTRUMENTS.

SPECIFICATION forming part of Letters Patent No. 310,590, dated January 13, 1885.

Application filed January 24, 1884. (No model.)

To all whom it may concern:

Be it known that I, ANDREW HYDE, a citizen of the United States, residing at Hatfield, in the county of Hampshire, and State of 5 Massachusetts, have invented certain Improvements in the Heads of Stringed Musical Instruments, of which the following is a specification.

The first part of my invention relates to 10 improvements in the mechanism used to rotate the "peg" or drum upon which a string is wound and by which it is tuned. The second part of my invention relates to the construction of the peg or drum, whereby the 15 end of a short string may be secured to the peg, or a long string be made fast at a point thereof, to cause it to be stretched simultaneously with the rotation of the peg. These improvements are fully illustrated in the accompanying drawings, in which—

Figure I is a side view of a violin - head. Fig. II is a plan view of the same, and Figs. III, IV, and V are enlarged details.

B is the gear upon the end of the drum C. 25 The drum C is in the usual manner collared or otherwise held in place in the head to extend from side to side.

D is the worm, held in bearings to be rotated by a convenient handle, d', and engage 30 with the gear B.

Heretofore the worm-gearing has been arranged to be inseparable, so that the revolution of the drum in either direction could only be a slow process; but by adapting the worm 35 D to be thrown at will from connection with the gear B, it will be seen that any portion of string remaining on the drum may be pulled, to rapidly release itself by revolving the drum.

By the provision of a convenient handle, 40 E, upon a prolongation of the axis of the drum C, at a point outside of gear B, a new string attached to the drum can be rapidly wound, as in the case of an ordinary peg, until near the proper pitch, and then be brought 45 into tune by the worm - shaft D, thrown into operative position at the last moment.

In Figs. I and II, as a convenient method of arranging a worm - shaft, D, removable at will, the shaft is shown in fixed journal-bearings d d, to be moved tangentially to the 50 gear B, the shaft having stops c c to limit the

distance it can be slid in either direction by bringing up against either the upper or lower journal-bearing d. The shaft D fits snugly enough to be held by friction in its bearings 55 when pushed up, as shown in Fig. I, and when operative, as shown in the same figure, the tension of the string acts through gear B to retain it in position.

In Fig. II one bearing d is shown, with the 60 shaft D removed.

Another method of arranging the worm-shaft D to be manually released from the gear B is shown in Fig. III, in which an upper journal-bearing e is pivoted in the side of 65 the instrument - head or in a plate attached thereto, and a lower bearing e' arranged to extend into and be movable in a slot, f, against a binding - spring, y, acting to retain said lower bearing at either end of its swing. In 70 the same figure, in dotted lines, is shown the position taken by the shaft D when swung to release gear B.

In the spools or drums of mechanical heads, as well as in the ordinary pegs, there are 75 many strings which cannot be utilized from being too short to have turns enough taken with their ends around the peg to hold; but by arranging axially within the peg or drum a screw to extend to the transverse hole through 80 the same I am able instantly to bind the string to the peg at an extreme end, or at any point in its length, so that the rotation of the peg is effective to at once bring a tension up-on the string. Though this may be accom- 85 plished by means of a perforation in the end of the screw through which the string is passed when coincident with the peg - hole, and binding the string upon a partial turn of the screw, I prefer the means shown in the 90 drawings, in which the end of a screw binds the string against the farther wall of the peg-hole.

In Fig. IV a section of the drum C of a mechanical head is shown having the screw H in 95 position to secure the string g, i being the ordinary hole through which the string is passed, and I the head of the screw, coming outside of the instrument in convenient reach of the fingers.

In Fig. I the perforated end of one peg is 96 shown with the screw H removed.

Fig. V shows the screw H as combined with an ordinary wooden peg, W.

Heretofore a winding-drum for strings in this class of instruments has been known in which the worm-wheel was disengaged from the drum by a longitudinal movement of the wheel with reference to the drum. This necessitated the cutting away and weakening of the drum. Such construction I do not claim.

10 Now, having described my invention, what I claim is—

1. In combination with the head of a stringed instrument, a winding-drum, a worm-wheel fixed to said drum outside the head, and a 15 worm movably mounted on the head so as to be shifted into or out of engagement with the worm-wheel, substantially as described.

2. The combination, with the head of a

stringed instrument, of a winding-drum, a worm-wheel secured to said drum outside the 20 head, and a worm-shaft mounted in a swiveled and a sliding bearing, so that the worm may be swung into or out of engagement with the gear-wheel, substantially as described.

3. The combination, with a cord-winding 25 peg or drum of a musical instrument, of a binding-screw arranged to extend from one end of the peg or drum and within the same to the hole therethrough, and adapted to, upon rotation, bind the string within said hole 30 and so secure it to the peg or drum, substantially as shown and described.

ANDREW HYDE.
